UNITED STATES PATENT OFFICE.

NICHOLAS A. HOVER, OF PATERSON, NEW JERSEY.

WARPING-MACHINE.

No. 921,403.

Specification of Letters Patent.

Patented May 11, 1909.

Application filed November 8, 1907. Serial No. 401,200.

To all whom it may concern:

Be it known that I, NICHOLAS A. HOVER, a citizen of the United States, residing at Paterson, in the county of Passaic and State 5 of New Jersey, have invented certain new and useful Improvements in Warping-Machines, of which the following is a specification, reference being had therein to the accompanying drawing.

10 My invention relates to warping machines, particularly to those warping machines which have what is termed the Swiss movement, or Swiss warping machines, in which sections of warp are successively laid 15 side by side on the reel. Such machines employ a reed-carriage which is moved laterally by power in laying a section of warp on the reel and at the completion of a section 20 is moved by hand to a new position to begin another section.

My invention is an improved carriage and novel means for imparting a lateral movement thereto.

In the drawings accompanying this specification is shown a warping machine embodying my invention and similar parts in the several views are designated by similar numerals.

Figure 1 is a transverse vertical section 30 on the line A—A in Fig. 2 showing the construction of the traveling carriage and its arrangement with relation to the frame on which it moves; Fig. 2 is a plan view thereof; Fig. 3 is an end view of parts 35 shown in Fig. 2; Fig. 4 is a view partly in section of parts of machine on the line —B—B— in Fig. 2; Fig. 5 is an enlarged view partly in section of shaft and tubular-worm sleeve adapted to slide longitudinally 40 thereon, parts being broken away; Fig. 6 is a skeleton view of a warping machine showing the arrangement of my improvement and means for driving the same; and Fig. 45 7 is a modified form of means for driving the traveling carriage.

In said drawings —1— is the frame, —1^a— the location of the take-off mechanism, which it is not deemed necessary to show in this application, —1^b— the end of 50 the frame where the feed mechanism and my improvement is located for supplying and laying the warp on the reel in sections with evenness and regularity, and —2— is the reel.

55 Mounted in suitable bearings in the frame

—1— is the main shaft —3— on the end of which is secured a sprocket wheel —16— which is connected by a sprocket chain —17— with a sprocket wheel —15— secured on the end of the shaft —14— to communicate motion to the latter shaft. The shaft —14— is provided with a longitudinal slot —14^a— to permit the tubular worm-sleeve or endless screw —18— to be moved along said shaft as required, the screw-pin —19— 60 engaging said slot —14^a— to cause the tubular worm-sleeve —18— to revolve with said shaft.

Stationary guide-bars —4— are secured to the frame and are provided with a graduated scale for measuring purposes as indicated by —4^a—, in Fig. 2. A sliding carriage 5 rests, stationary, on the bars 4— while a section of warp is being laid on the reel 2, said carriage being adapted to be 70 moved by hand to a new position as fast as each section of warp is completely laid on the reel and the laying-on of a fresh section of warp is to be commenced. Lugs —6— 75 on the carriage —5— fit about the bars —4— and the shaft —14— passes through the carriage-lugs —5^a— so that when it is desired to move the carriage —5— at the completion of one section of warp on the reel, it is only necessary to disengage the thumb-screw 7 by turning the same to permit the carriage to be moved along the bars, carrying with it the tubular worm-sleeve, until the carriage is in the position desired 80 when the thumb-screw —7— may be tightened again and the process of laying the next section of warp —8— on the reel —2— 85 may be commenced the light upper carriage —9— carrying the reed —11— and the rollers —10— being caused to slide 90 upon the slide-rods —8— which are secured to the lower carriage —5— by means of the finger —20—, which is secured to and depending from the lug —9^a— of the upper frame —9—, engaging the thread of the 95 tubular worm-sleeve —18—. An arm —12— 100 may be secured either to the upper sliding or traveling carriage —9— or to the movable carriage —5—, it being preferable to have it secured to the latter as the traveling carriage —9— is then lighter and is more easily operated. The arm —12— carries the large reed —13— in a suitable support at the end thereof.

In other warping machines an endless 110

screw the length of the frame is employed and but one large carriage which is moved either by said endless screw by power or by hand the latter being the case at the completion 5 of the laying of each layer of warp-thread on the reel. Each time it is moved by hand the carriage is moved a distance equal to the length of the carriage plus the length of the width of the section previously 10 laid on the reel; but I have a tubular worm-sleeve —18— which is very short as shown in Fig. 2 and is moved with the carriage —5— when the latter is moved, the worm-sleeve sliding on the slotted shaft —14—. 15 When the carriage —5— is secured in position by tightening the screw —7— power is communicated to the shaft —14— causing it and the tubular worm-sleeve 18 thereon to revolve engaging the finger —20—, or 20 some equivalent such as the worm-wheel —21— shown in the modification in Fig. 7, to cause the upper traveling carriage —9— to move with precision and to evenly distribute the warp-thread on the reel —2—. 25 until a section of the required width is completed, which requires but little power, my traveling carriage being only four inches wide and very light while the old style carriage for straight warping is very heavy 30 and requires some strength to move it by hand.

In Fig. 3, —8^a— is a collar secured on the shaft —8— at the point where it is desired to start or stop the carriage —9—, and 35 in Fig. 7 —22— is a revolving shaft carrying the worm-wheel 21 and 23^a means for locking the same against rotation, so that the lateral movement of the carriage will follow on rotating the worm-sleeve.

40 When the machine is in operation the tension of the warp moves the reed —13— on the rollers —13^a— as the carriage —9— travels, the arm —12— which carries the reed —13— being secured to the platform 45 of the movable carriage —5—, as shown in Fig. 7. The collar —8^a— is secured on the bar —8—, where desired according to the width of the sections of warp, so that the traveling carriage —9— will operate or 50 slide always along the middle portion of the bars —8—.

It is obvious that the light carriage —9— is moved with facility and precision by the short worm-sleeve —18— which is driven 55 by the shaft —14— when the machine is in operation laying a section of warp on the reel and that it is economical in construction effecting a saving in time and labor.

In practice the distributing of the warp 60 on the reel by the light traveling carriage —9—, which is mounted on the carriage —5—, has many advantages, over the old style of one heavy carriage and a long endless screw, both in ease of operation and 65 efficiency.

With this description of my invention, what I claim as new and desire to secure by Letters-Patent, is—

1. In a warping machine, the combination with the frame reel and reel shaft journaled in said frame, of another shaft also journaled in said frame, a sprocket wheel on the end of each of said shafts, a sprocket chain passing around said sprockets, the latter shaft being provided with a longitudinal slot, a tubular worm-sleeve loosely arranged on said shaft and adapted to be moved longitudinally thereon and to be driven thereby, guide bars in said frame, a carriage movable on said bars to move the said 70 worm-sleeve along the slotted shaft, means for securing said movable carriage to said bars where desired, guide-bars on said movable carriage, another movable carriage on said bars, means operatively connecting 75 said last mentioned carriage and the said worm-sleeve to move the latter carriage on said guide-bars, a reed and rollers carried by said last-named carriage, and a laterally movable reed carried by the first mentioned 80 carrier, substantially as set forth.

2. In a warping machine, the combination, with the frame and the reel journaled therein, of a manually movable carriage arranged in the frame for movement laterally 95 of the reel, another carriage carried by the first carriage and movable laterally of the reel on said first carriage, and means for effecting the movement of the second carriage on the first, substantially as described. 100

3. In a warping machine, the combination, with the frame and the reel journaled therein, of a manually movable carriage arranged in the frame for movement laterally 105 of the reel, means for securing said carriage in fixed relation to the frame, another carriage carried by the first carriage and movable laterally of the reel on said first carriage, and means for effecting the movement of the second carriage on the first, substantially as described. 110

4. In a warping machine, the combination, with the frame and the reel journaled therein, of a manually movable carriage arranged in the frame for movement laterally 115 of the reel, another carriage carried by the first carriage and movable laterally of the reel on said first carriage, and means for effecting the movement of the second carriage on the first carriage comprising a rotary member movable with the first carriage laterally of the reel, substantially as described. 120

5. In a warping machine, the combination, with the frame and the reel journaled therein, of a manually movable carriage arranged in the frame for movement laterally 125 of the reel, another carriage carried by the first carriage and movable laterally of the reel on said first carriage, and means for 130

- effecting the movement of the second carriage on the first carriage comprising a rotary splined shaft and a screw-sleeve arranged on said shaft and movable with the first carriage laterally of the reel, substantially as described.
6. In a warping machine, the combination, with the frame and the reel journaled therein, of a manually movable carriage arranged in the frame for movement laterally of the reel, another carriage movable relatively to the first carriage laterally of the reel, and means for effecting the lateral movement of the second carriage relatively to the first carriage comprising a rotary member movable with the first carriage laterally of the reel and mechanism disconnectively connecting said member with the second carriage, substantially as described.
7. In a warping machine, the combination, with the frame and the reel journaled therein, of a manually movable carriage arranged in the frame for movement laterally of the reel, another carriage arranged in the first carriage for movement laterally of the reel in said first carriage, means for effecting the movement of the second carriage in the first carriage, a fixed gage, and means for ad-
- justably securing the first carriage in the frame with reference to said gage, substantially as described. 30
8. The combination with the frame and a driving shaft journaled therein, of guide-bars secured to said frame, a carriage arranged to be moved by hand on said bars, 35 guide-bars secured on said carriage, a traveling carriage adapted to move on said last mentioned guide-bars, and means operatively connecting said traveling carriage with the driving shaft, substantially as set 40 forth. 45
9. The combination with the frame, of two movable carriages, one above the other, the lower carriage movable by hand on said frame, the upper carriage carrying a reed and traveling upon the lower carriage, a movable reed on the lower carriage, and means for causing the upper carriage to travel upon the lower one, substantially as set forth. 50

In testimony whereof I affix my signature in presence of two witnesses.

NICHOLAS A. HOVER.
